UNITED STATES PATENT OFFICE.

GEORGE W. WHITEMAN, OF PHILADELPHIA, PENNSYLVANIA, ASSIGNOR TO FROG SWITCH AND MANUFACTURING COMPANY, OF CARLISLE, PENNSYLVANIA, A CORPORATION OF PENNSYLVANIA.

GUARD RAIL.

Application filed March 9, 1925. Serial No. 14,299.

My invention relates to guard rails of unit construction and the main object of my invention is to provide an efficient structure in the form of an integral body which shall 5 possess all of the characteristics required in a guard rail, and at the same time provide a structure materially lighter than the guard rails heretofore in use.

My improved guard rail is preferably 10 made of manganese steel, although not limited to a structure of such metal, and it comprises a longitudinal member constituting the guard rail proper, supported by and integrally connected to chairs adapted to 15 be mounted upon the ties supporting the main rail.

A further object of my invention is to provide a guard rail structure comprising the longitudinal member or rail proper, 20 plate supports or chairs arranged to overlie the ties, with angular braces integrally connecting said parts.

A further object of my invention is to provide the tie-engaging plates or chairs 25 with side flanges which reinforce these plates and may serve also as anti-creepers.

These and other features of my invention are more fully described hereinafter; reference being had to the accompanying drawings, in which:

Figure 1, is a plan view of my improved guard rail structure.

Fig. 2, is a side elevation of the same.

Figs. 3, 4 and 5, are cross sectional views 35 of the guard rail structure taken on the lines III—III, IV—IV, and V—V, Fig. 1, and Fig. 6, is a sectional view illustrating a detail of my invention.

In the drawings, A represents the main 40 rail of the permanent way, shown in the present instance as supported by ties B.

Disposed alongside said main rail A, in proper relative position with respect to the same and in substantial parallelism is the 45 unit guard rail structure constituting my present invention, made in the form of an integral body.

My improved guard rail structure comprises the rail proper, indicated at 1, which 50 may be substantially T-shape in cross section; tie-engaging plates 2, which are substantially flat and preferably provided with depending reinforcing flanges 2^a flanking the ties, and angular braces or supporting brack-

ets 3, diagonally disposed as indicated in Fig. 1, and inclined from the guard rail proper, downwardly, to one end of the tie-engaging plates 2. These braces may be substantially rectangular in cross section, or they may be longitudinally corrugated, as 60 indicated at x, Fig. 6.

The tie-engaging plates and the angular braces disposed in proper position to resist the thrust of lateral pressure applied to the guard rails constitute in effect, chairs to support the guard rail integrally connected to said braces.

The guard rail proper, as already noted, is substantially T-shape in cross section, and for the purpose of adding additional stiffness thereto, it may be provided with a lateral reinforcing flange 5, having an undulating edge 5^a and in addition, the lower edge of its body may be undulating, as indicated at 5^b.

At the ends of the guard rail, I preferably provide inwardly extending portions in the form of shelves 6, the inner edges of which may underlie the head of the main rail A, and these shelves are preferably integral 80 with the end bracing members which may be of the shape indicated at 3^a in Fig. 5, and underlie the main rail.

To further lighten the structure, the tie-engaging plates 2, may be apertured as indicated at 2^b. The tie-engaging plates are notched at 2^c for the accommodation of spikes or other form of securing means, whereby they may be fastened to the ties, and the opposite ends of these plates may have apertures 2^d for a similar purpose; such apertures 2^d having stepped walls permitting lateral adjustment of the guard rail structure with respect to the main rail A.

The ends of the guard rail are flared away 95 from the main rail, and the upper surface may be slightly beveled as indicated at 1^a.

It will be noted that my improved guard rail structure is materially lighter than structures heretofore proposed, in that the 100 guard rail proper is supported wholly by the angularly disposed braces which integrally connect the same with the tie-engaging plates; there being no other web connection between the guard rail proper and said 105 tie-engaging plates. In addition, the guard rail is of much lighter cross section and is stiffened laterally and vertically by the

flanges having the undulating edge contour.

It will be further noted that the angularly disposed braces 3 are connected to the guard rail proper at substantially equally spaced points and that these braces, with the tie-engaging plates provide, in effect, supporting chairs.

I claim:

1. In a guard rail structure, the combination of the guard rail proper, a series of tie-engaging plates from which said guard rail is spaced, and a plurality of braces connecting each of said tie-plates to the guard rail.

15 2. In a guard rail structure, the combination of the guard rail proper, and a plurality of supporting chairs therefor comprising a series of tie-engaging plates from which said guard rail is spaced, and a plurality of braces integrally connecting each of said tie-plates to the guard rail.

25 3. In a guard rail structure, the combination of the guard rail proper, a series of flanged tie-engaging plates from which said guard rail is spaced, and a plurality of braces connecting each of said tie-plates to the guard rail.

4. In a guard rail structure, the combination of the guard rail proper, and a plurality of supporting chairs therefor comprising a series of flanged tie-engaging plates from which said guard rail is spaced, and a plurality of braces integrally connecting each of said tie-plates to the guard rail.

35 5. In a guard rail structure, the combination of the guard rail proper, substantially T-shape in cross section, a series of tie-engaging plates from which said guard rail is spaced, and a plurality of braces connecting each of said tie-plates to the guard rail.

40 6. In a guard rail structure, the combination of the guard rail proper substantially T-shape in cross section, and a plurality of supporting chairs therefor comprising a series of tie-engaging plates from which said guard rail is spaced, and a plurality of braces integrally connecting each of said tie-plates to the guard rail.

5. In a guard rail structure, the combination of the guard rail proper, a series of tie-engaging plates from which said guard rail is spaced, and a plurality of angularly disposed braces connecting said guard rail to the tie-plates.

55 8. In a guard rail structure, the combination of the guard rail proper, and a plurality of supporting chairs therefor comprising a series of tie-engaging plates from which said guard rail is spaced; each of said tie-engaging plates having a plurality of angularly disposed braces forming integral connections between said plates and the guard rail.

60 9. In a guard rail structure, the combination of the guard rail proper, a series of tie-

engaging plates from which said guard rail is spaced, and pairs of braces connecting said guard rail to each of said tie-plates.

10. In a guard rail structure, the combination of the guard rail proper, and a plurality of supporting chairs therefor comprising a series of tie-engaging plates from which said guard rail is spaced, and pairs of braces integrally connecting said guard rail to each of said tie-plates.

15 11. In a guard rail structure, the combination of the guard rail proper, a series of tie-engaging plates, and pairs of angularly disposed braces connecting said guard rail to each of said tie-plates.

12. In a guard rail structure, the combination of the guard rail proper, and a plurality of supporting chairs therefor comprising a series of tie-engaging plates and pairs of angularly disposed braces connecting said guard rail to each of said tie-plates.

13. In a guard rail structure, the combination of the guard rail proper, a series of tie-engaging plates from which said guard rail is spaced, and pairs of angular braces laterally disposed with respect to said guard rail and connecting the same with the respective tie-plates.

14. In a guard rail structure, the combination of the guard rail proper, and a plurality of supporting chairs therefor comprising a series of tie-engaging plates from which said guard rail is spaced, and pairs of angular braces laterally disposed with respect to said guard rail and integrally connecting the same with the respective tie-plates.

15. In a guard rail structure, the combination of the guard rail proper having a flange with an undulating edge, tie-engaging plates, and pairs of braces disposed at one end of each of said tie-engaging plates for supporting said guard-rail.

16. In a guard rail structure, the combination of the guard rail proper having a flange with an undulating edge, tie-engaging plates from which said guard rail is spaced, and pairs of angularly positioned braces disposed at one end of each of said tie-engaging plates for supporting said guard rail.

17. In a guard rail structure, the combination of the guard rail proper substantially T-shape in cross section; said guard rail having a laterally extending flange with an undulating edge, tie-engaging plates from which said guard rail is spaced, and pairs of braces forming integral connections between said plates and said guard rail.

18. In a guard rail structure, the combination of the guard rail proper substantially T-shape in cross section; said guard rail having a laterally extending flange lengthwise of the same with an undulating edge and a depending flange lengthwise of the same with an undulating edge, a series of tie-en-

gaging plates, and pairs of braces integrally connecting said tie-engaging plates with said guard rail.

19. In a guard rail structure, the combination of the guard rail proper substantially ⁵ T-shape in cross section; said guard rail having a laterally extending flange lengthwise of the same with an undulating edge and a depending flange lengthwise of the same with ¹⁰ an undulating edge, a series of tie-engaging

plates and pairs of diagonally disposed braces integrally connecting said tie-engaging plates with said guard rail.

20. In a guard rail structure, the combination of the guard rail proper, a series of tie-¹⁵ engaging plates, and corrugated braces connecting said tie-plates and guard rail.

In witness whereof I have signed this specification.

GEORGE W. WHITEMAN.
